To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing, which forms a part thereof.

In the drawing, the sole figure of which is a plan view of a piece of the textile fabric embodying the design of the present invention, the cloth depicted is of a single color.

The design motif includes horizontal rows of reversely curved lenticles alternating with horizontal rows of elongated areas having oval ends of unequal fullness and having protuberances on their upper sides indenting the lower sides of the adjacent lenticles, said lenticles and elongated areas being delineated by loose irregular and elevated stitches.

A repeated unit is indicated in the frame of broken lines in Figure 1.

I claim:

The ornamental design for textile fabric as described and shown.
